United States Patent Office.

SINEUS E. TOTTEN, OF BROOKLYN, NEW YORK, ASSIGNOR TO HIMSELF
AND CYRUS L. TOPLIFF, OF THE SAME PLACE.

Letters Patent No. 65,843, dated June 18, 1867.

IMPROVED AWL.

The Schedule referred to in these Letters Patent and making part of the same.

TO ALL WHOM IT MAY CONCERN:

Be it known that I, SINEUS E. TOTTEN, of Brooklyn, in the county of Kings, and State of New York, have invented a new and useful improvement in Awls; and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

The object of this invention is to facilitate the operation of sewing leather, and all substances of a similar nature, and it applies to the arts, particularly in the process of shoe and harness-making, where bristles are used on the thread. And the invention consists in forming the awl (whether straight or curved, as represented in the drawing,) with a groove on its side, in which groove the bristle is passed through the leather, as will be hereinafter more fully described, reference being had to the accompanying drawing, forming a part of this specification.

Figure 1 represents a view of the operation of sewing leather.

Figure 2 represents an ordinary shoemaker's awl with a groove in its upper side.

Similar letters indicate corresponding parts.

A is the awl; B represents the leather, and C is the thread, with the bristle passed through the leather in the groove of the awl. The groove is seen in fig. 2, at D. It commences near the point of the awl, being either round or angular in form, and extending longitudinally in the awl towards the handle somewhat farther than the awl is intended to penetrate.

In the process of sewing, the operator, when he pierces the leather, usually gives the awl a rapid rotary motion for the purpose of making a clear, round hole through the leather, and also because the awl penetrates the leather easier by so doing. It is reaming out the hole, not so much for the purpose of making it larger as to make a clean hole which will not close when the awl is withdrawn. When the awl has been forced through the leather in this manner, and a clean, round hole is formed, as is ordinarily done, it will partially close up when the awl is withdrawn, and it requires a sharp eye and much skill to put the bristle in the hole, although it may be in some measure guided by the receding point of the awl.

With my improved awl there is no difficulty whatever. The awl is not withdrawn until the bristle is passed through in the groove, which is done with the utmost facility. It is a plain and straight-forward operation, which requires no straining of the eyes and no second trial. It is one of those simple devices by which a serious difficulty is overcome, the advantages of which must be obvious to all.

Having thus described my invention, I claim as new, and desire to secure by Letters Patent—

As a new article of manufacture, an awl, having a longitudinal groove, D, as herein set forth for the purpose specified.

S. E. TOTTEN.
